UNITED STATES PATENT OFFICE.

JOHN A. BACON, OF PHOENIX, ARIZONA TERRITORY.

GATE.

SPECIFICATION forming part of Letters Patent No. 437,766, dated October 7, 1890.

Application filed February 17, 1890. Serial No. 340,764. (No model.)

To all whom it may concern:

Be it known that I, JOHN A. BACON, a citizen of the United States, residing at Phoenix, in the county of Maricopa and Territory of Arizona, have invented a new and useful Gate, 5 of which the following is a specification.

My invention relates to improvements in gates, and more particularly to that class thereof known as "sliding;" and it consists of, 10 certain novel features hereinafter described, and illustrated in the accompanying drawings, in which—

Figure 1 is a perspective view of my improved gate. Fig. 2 is a plan view of the same, 15 partly open. Fig. 3 is a detail view to show the wedge on the gate and the keeper on the frame. Fig. 4 is a perspective view of my improved gate in its double form opening at the center.

20 In carrying out my invention I erect along the line of the fence a frame, preferably comprising the posts B B', to the upper ends of which I secure the beam C. A beam D is arranged at right angles to the beam C and is supported a slight distance above the same. This beam D is braced by the inclined braces E, extending from the center post B' to the beam and from a standard F, arranged adjacent to the center post, to the beam, the said, 25 standard F forming with the center post a guide to prevent the gate's swaying laterally. On the side of the beam C, I secure a rail G, and the gate H is provided at its upper end with the rollers I, which engage and ride upon the upper edge of the rail. On the upper side, 30 of the beam C, and at a suitable distance from the opposite sides of the center post, I secure the pulleys J, and at the ends of the beam D, I secure the pulleys K, as shown. The operating-ropes extend around the pulleys J K and, 35 over the rollers I, and have their ends secured to the upper ends of the rods L, the lower ends of said rods being secured to the free end of the spring-latches M, which are secured on the gate and adapted to engage lateral pins, 40 N, projecting from the end post B and from a supplemental gate, if one be used. The operating-ropes, it will be observed, extend to the opposite ends of the gate and then pass, 45 inward to the pulleys J and thence outward to the pulleys K, their ends depending from the said pulleys K. The loops formed by the

depending ends of the ropes carry the weights O, which are hung from grooved rollers or pulleys P, fitted in the said loops.

55

On the side of the gate-opening, at the front end of the gate, I locate the bracket or keeper Q, and to the lower front corner of the gate I secure the wedge or guide R, which is adapted to enter the said keeper and thereby hold the gate close to the supporting-frame, as will be readily understood.

60

The construction and arrangement of the several parts of my device being thus made known, the operation of the same, it is thought, 65 will be readily understood.

In operation, a person approaching the gate on horseback or in a vehicle will draw downward on one of the ropes S leading to the adjacent weight O, thereby causing the operating-rope to exert an upward pull on the front latch, so as to release the same, when the continued downward pull on the rope S will cause the gate to slide or roll rearward, and thus open the gateway so as to permit travel therethrough. Upon reaching the other side of the gate the closing-rope T at that side is drawn downward, so as to close the gate. It will be observed that the latches automatically engage the locking-pins and thus effectually hold the gate in its closed or open positions, so that premature movement of the same will be prevented. The arrangement of the operating-rope is such as to effect an economy in the quantity of rope required, 70 and also transmit the force applied to the rope directly to the end of the gate, so as to operate the same. The weights at the ends of the rope being hung from rollers, as shown and described, the rope can readily slip past the weight, so as to accommodate itself to a 75 change in the position of the gate.

80

The gate is very simple in its construction and its advantages are thought to be obvious.

85

In the construction shown in Fig. 4, the arrangement of parts is similar, with the exception that the pin N at the front edge of the gate is inserted in the vertical bar in the front edge of the other gate, whereby when the two gates come together they will be locked in closed position, as will be understood. In this case also the keeper Q is formed of a block having a transverse recess beveled in both directions, whereby it forms a double- 90

95

100

wedge-shaped slot for the entry of the lower ends of the front bars of the gates. In this construction when the opening-rope S is drawn the front edge of the left-hand gate is drawn 5 rearwardly, and the second opening-rope S' is drawn by said front edge over a pulley at the extreme right of the frame and draws the front edge of the right-hand gate open also. When the closing-rope T is drawn upon, it 10 draws the outer edge of the left-hand gate inwardly, (precisely as in Fig. 1,) and the second closing-rope T', which is connected to said outer edge, is drawn over a pulley at the extreme left of the frame and exerts an inward pull upon the front bar of the right-hand gate, as will be clearly understood. It 15 will be obvious that the opening-ropes have the same length of stroke as the closing-ropes, except in precisely opposite directions, so that 20 the movement of one compensates for the movement of the other, and the weights O will remain at the same height from the ground, while the loop formed by the supplemental opening and closing ropes S' T' operates the 25 supplemental (in this case the right-hand gate) from the other gate, the latter being

operated by the main opening and closing ropes.

Having thus described my invention, what I claim, and desire to secure by Letters Patent, is—

In a gate, the combination, with the supporting-frame having a pin in its left outer post, and two gates traveling in said frame, the right gate also having a pin in its inner 35 edge, of latches connected to each edge of the left gate and adapted to engage said pins, a looped rope passing over rollers on both outer posts of the frame, to the opposite sides of which loop the two gates are connected, 40 and opening and closing ropes connected to said latches and led over pulleys to a distance from the frame, the whole operating substantially as described.

In testimony that I claim the foregoing as 45 my own I have hereto affixed my signature in presence of two witnesses.

JOHN A. BACON.
